MEANS FOR CLEANING WELL SCREENS

Norris E. Gunderson, Mishawaka, Ind., assignor to
Layne-Northern Company, Incorporated, Mishawaka, Ind., a corporation of Indiana

Application June 15, 1942, Serial No. 447,069

2 Claims. (Cl. 166—20)

This invention relates to well cleaners, and specifically contemplates means for washing the clogged perforations of well casing screens and portions of the surrounding strata by segregating limited areas of the screen structure in order that pressure may be concentrated thereon and flow be accelerated therethrough, whereby deposits on the screen structure and in the adjacent strata may be dislodged, broken up and removed.

Much time and study has been heretofore directed to this question of segregating areas of the screen, with rather limited success, it having been found extremely difficult to make a device which could be readily shifted from time to time and which when so shifted could be depended upon to accomplish segregation.

The objects of the present invention are:

To provide a simple and efficient structure adapted to seat against the interior surface of a well screen and outline an area of such screen to be cleaned;

To provide means for shifting the device into contact with the screen and for forcing it into sealing contact with and withdrawing it from the screen;

To provide means for compelling liquid supplied to the device and pulsated to flow alternately outward and inward through definitely restricted screen areas into and from the surrounding strata;

To provide means for shifting the device longitudinally or laterally around the screen to permit positioning and contacting;

To provide a device for segregating screen areas adapted to be secured to the lower end of a well string, for shifting and operation;

To provide a device of the character described which is effective to segregate diametrically opposite screen areas concurrently, and operate concurrently thereon.

The means by which the foregoing and other objects are accomplished and the method of their accomplishment will readily be understood from the following specification upon reference to the accompanying drawings, in which:

Fig. 1 is a vertical sectional elevation of a well screen in place in a well with screening aggregate therearound, showing a face side of the cleaning apparatus in elevation.

Fig. 2 is a fragmentary side elevation on a reduced scale showing a modified form of the device.

Fig. 3 is a sectional side elevation of the apparatus at right angles to Fig. 1, with the screen

shown in section only and the segregating chambers retracted from the screen.

Fig. 4 is an enlarged fragmentary plan view taken on the line IV—IV of Fig. 3, showing the pressure exerting mechanism.

Fig. 5 is a corresponding fragmentary elevation taken on the line V—V of Fig. 4.

Fig. 6 is a sectional plan taken on the line VI—VI of Fig. 3.

10 The device is for use with a well string including pumping apparatus and a discharge column extending to and discharging above ground level.

In its preferred form, the device comprises a pair of open face chambers, each preferably a shallow box 11, each having shallow side walls 13, end walls 15, and a bottom or back wall 19, being entirely open on the top or front. The bottom wall 19 of each is provided with a slot 21 extending centrally throughout a major portion 15 of its length. These boxes are stood on end bottom toward bottom, so that their open tops or fronts face outward, and the bottom slots are vertically disposed.

Conformingly secured around the periphery of 25 the open outwardly faced front of each box, or chamber, respectively, is a continuous contacting member or gasket 23 of soft rubber, the outer edge of this gasket in plan, along the upper and lower ends of the box, arcuately conforming to 30 the curvature of the well screen 25 with which it is to be used, and along the sides being straight to likewise conform along vertical lines. The boxes are disposed in diametrically opposed relation, with the gaskets carried thereby, outwardly 35 faced and with the slots in the backs vertically and inwardly disposed.

Secured to the backs 19 of the boxes as by 40 welding, are vertically disposed pipes 27, each pipe being closed at its bottom end and slotted to conform to the slot in the related box, the welding sealing the pipes to the boxes around 45 their respective slots. The two pipes extend upward in substantial parallelism to and are connected into the closed end 28 of a well pipe 29 through which liquid, as water or oil, may be withdrawn in usual manner, as by pumping mechanism 38, or be released to surge downward. To increase flexibility, one (or both) of the pipes may include a flexible coupling 27-A.

50 31 is a well column which extends to the ground surface, the structure serving also to raise and lower or turn the device in the well. The two pipes 27 are spaced apart to permit insertion therebetween of a pair of spaced pins 33 which 55 effect a cam member and are carried by a bell

crank lever 35, this lever preferably including duplicate arms 35-A, 35-B, disposed on opposite sides of the pipes 27 and connected together by the pins 33 between the pipes. The arms 35-A, 35-B extend laterally outward from the pins 33 and are connected by a third pin 37. From this third pin a link 39 extends upwardly alongside one of the pipes 27 and terminates in a bail 41 to which is connected a cable 43 extending to an accessible point about the surface of the ground. Preferably the upper end of the link 39 is guided, as by a bracket 45 conveniently secured to one of the pipes 27.

The diameters of the pins 33 and sizes of the pipes 27 and projection of the boxes 13 and their gaskets are such that when the pins 33 are vertically alined one above the other, the gaskets 23 may be held well clear of the screen 25. Means, preferably a tension spring 47, connected between the lower ends 17 of the boxes, may be used to hold the boxes in retracted position.

To accomplish centering of the boxes transversely to the direction in which they are spread apart, outwardly bowed flat members of resilient material 49 are secured at their upper ends on opposite sides of the tube 28 and extend downwardly to and are secured at their lower ends to one of the pins 33, being here shown as connected to the upper of such pins. This connection serves not only to secure and brace the lower ends of the bowed flat members or guides, but the guides through the pin connection, serve to support the bell crank member 35 and provide a fulcrum against which the pull of the link 39 reacts to effect spreading apart of the boxes by the camming action of the spaced pins.

While the preferred type of structure includes two chambers which are moved apart by the camming action, it will be understood that one only of the chambers 11 and tubes 27 may be used, or as shown in Fig. 2, a similar single chamber 11-A may be used, mounted on the lower end of the well pipe 28-A and the chamber be displaced laterally by action of the camming member carried by the bell crank lever 35-C, against the well screen 25-A, such action also laterally displacing the well pipe 28-A, and the well string thereabove.

It will further be understood that the details are largely introduced for the purpose of illustration and may be varied from except as in a claim specifically set out.

To use the device the pump column and pumping machinery carried thereby is removed from the well and usually, though not necessarily, to effect saving in wear and tear on the regular pump, the pumping mechanism is replaced by a more rugged pump better adapted to cleaning purposes.

The present device is securely coupled into the lower end of the pumping mechanism and by means of the well column is lowered into the well until the boxes or chambers 11 overlie a section of the screen which is to be cleaned, this usually being at either the extreme upper or extreme lower end of the screen and more conveniently being at the lower end in order that the apparatus may be lowered until it seats and thereafter be progressively moved upward as cleaning progresses until the usually known length of screen has been covered, or until the boxes, eventually seating inside the solid well casing, indicate by stoppage of well discharge that such position is reached.

In this movement into the screen area, and in

the screen area, the bowed members 49 hold the boxes properly centered transversely to the direction in which they are to be moved apart.

The device having been positioned opposite to screen areas which are to be cleaned the cable 43 is pulled upwardly and through the bell crank lever 35, shifts the pins 33 from positions vertically, one above the other, out of such alinement, forcing the pipes 27 apart, and through this movement forcing the gaskets 23 into sealing contact with opposite screen areas, thus outlining and segregating screen areas for treatment. Thereafter the pumping mechanism may be started up to draw liquid violently inwardly from the surrounding strata through the segregated screen areas and stopped or even reversed to cause discharge outwardly through the same areas by pressure of the liquid in the pump column or direct reversed pumping action. This surging action is continued until cleaning of the areas is accomplished, pumping to discharge being run from time to time to determine by showing of detritus in such discharge, progress of the cleaning.

After the first areas are cleaned, clamping action is released, the pump column is turned to shift the boxes to cover adjoining areas of the screen at the same level, the boxes are reclamped and the pumping operation repeated. Usually the boxes are made of such width that one-fourth the area, or one-sixth the area, of the screen is covered by each box so that full cleaning of a horizontal belt may be accomplished by two or three shifts, as the case may be. After the first area belt is cleaned, the apparatus is released, and raised or lowered, as the case may be, to cover a next higher or lower area and the operations repeated, until the entire screen area has been covered, after which the device is removed from the well, the regular pumping apparatus replaced and the well is again put in operation.

I claim:

1. In apparatus for cleaning the screen of a well, a structure including a tubular well string supported from the ground surface and pumping means operatively connected therewith, a pair of open faced chambers disposed below said string, a pair of pipes secured to, opening into, and extending downwardly from, said string, each pipe respectively carrying adjacent its lower end one of said chambers and opening thereinto, to position said chambers relatively to said string and form passageways between said string and said chambers, said chambers being held by said pipes with their open faces facing outwardly toward substantially diametrically opposite screen areas, each of said chambers having around its open face a gasket having a screen contacting surface of shape conforming to the periphery of its said screen area, and means carried by said structure manually operable to shift said chambers apart to effect sealing contact of their respective open faces with said opposite screen areas, said means including a camming member disposed in part between said pipes, and having a laterally extending portion, and operating linkage pivotally secured to said extending portion adjacent the outer end thereof, and extending upward along said well string to the ground surface.
2. In apparatus for cleaning the screen of a well, a structure including a well string supported from the ground surface, and pumping means operatively connected therewith, a pair of

open faced chambers disposed below said string, a pair of pipe-like members secured to and extending downward from said string, each of said members respectively being rigidly secured adjacent its lower end to one of said chambers and opening thereinto, said members positioning said chambers below said string for coordinated movement therewith, said members opening into said string and forming passageways between said string and said chambers, said chambers being held by said members with their open faces facing outwardly toward substantially diametrically opposite screen areas, each of said chambers having around its open face a gasket having a screen contacting surface of 15

5 shape conforming to the periphery of a said screen area, means carried by said structure manually operable to shift said chambers apart to effect sealing contact of their respective open faces with said opposite screen areas, said means including a camming member disposed in part between said members, and having a laterally extending portion, and an operating member pivotally secured to said extending portion adjacent the outer end thereof, and extending upward along said well string to the ground surface; and tension means oppositely secured to said chambers acting to withdraw said chambers from screen contact.

NORRIS E. GUNDERSON.
